UNITED STATES PATENT OFFICE.

ANDREW G. STEINBRENNER, OF ST. LOUIS, MISSOURI.

GRAIN-CAR DOOR.

SPECIFICATION forming part of Letters Patent No. 745,259, dated November 24, 1903.

Application filed May 25, 1903 Serial No. 158,710 (No model.)

To all whom it may concern:

Be it known that I, ANDREW G. STEINBRENNER, a citizen of the United States, residing in the city of St. Louis, in the State of Missouri, have invented certain new and useful Improvements in Grain-Car Doors, of which the following is a full, clear, and exact description, reference being had to the accompanying drawings, forming part of this specification.

My invention relates to that character of grain-car doors in which openings are provided for the exit of grain from the interior of the car previous to opening the door completely and also an improvement in the guideway face-strips against which the guide-studs of the door operate.

My invention consists in features of novelty hereinafter fully described, and pointed out in the claims.

Figure I is a front elevation of a grain-car door constructed in accordance with my improvement. Fig. II is a vertical section taken on line II II, Fig. I. Fig. III is an inside elevation of one of the door-posts of a grain-car with the guideway face-strips applied thereto and a fragment of the grain-door. Fig. IV is a horizontal section taken on line IV IV, Fig. II. Fig. V is a horizontal section taken on line V V, Fig. II, through the door and one of the gate guide members. Fig. VI is a perspective view of one of the gate guide members.

1 designates the posts of a grain-car door-way. These posts are rabbeted, as seen in Figs. II and IV, the rabbets therein extending to the inside faces of the posts within the car. The production of the rabbets referred to provides for guideways 2 between a forward guide-strip 3 having flanges 4 and inner guideway face-strips 5 having flanges 6, disposed opposite to the flanges 4 of the strips 3, but separated therefrom, as seen in Figs. II and IV. The guideway face-strips 5 are provided with series of ears 7, that project beyond the rabbeted portions of the door-posts and through means of which said face-strips are secured to the posts by screws 8 passing through said parts. At the upper end of each guideway face-strip is a socket 9. These guideway face-strips are subjected to considerable strain by the guide-studs of a

grain-car door, and unless additional means for their retention to the doorway-posts other than bolts or screws is provided they frequently become loosened as a result of the strain to which they are subjected. For the purpose of strengthening their connection to the posts I provide studs 10, projecting from their rear faces into recesses in the posts, as seen in Figs. III and IV. These studs afford resistance to the lateral movement of said face-plates and relieve the fastenings connecting them to the posts of strain, so that the attachment of the strips remains secure.

11 designates a door positioned at the inside of the car against the posts 1 and slidably connected to said posts by studs 12, provided with heads 13, (see Fig. IV,) which operate in the guideways 2 between the guideway-strips 3 and 5. These studs 12 are designed to travel upwardly in said guideways in the raising of the door 11, so that the studs may be passed into the sockets 9 of the guideway face-strips 5 when the door is suspended beneath the roof of the car in the usual manner. It is during this movement of the door and the travel of the guide-studs that said guideway face-strips are subjected to the strain hereinbefore referred to.

In the door 11 are gateways 14 through which the grain within the car equipped with my door is first discharged in emptying the car. These gateways are controlled by gates 15, held in the manner to be presently described. The gates 15 are pliable and resili- 85 ent, being of sheet metal, and each gate is provided with a handle 16, by which the gate may be engaged to move it to and from said gateway.

17 designates gate guide members secured to the door 11 at the sides of the gateways therein by bolts or screws 18, that pass therethrough. (See Fig. I.) Each of the gate guide members is composed of a side wall 19, bearing a curved outer flange 20, extending approximately the full length of the guide member, and an inner flange 21, located at the lower end of the member and extending parallel with the adjacent portion of the outer flange 20, as seen in Figs. I and VI. The flange 21 is straight throughout its length, but is preferably inclined forwardly toward the curved flange 20, as seen in Fig II. Projecting from

the side wall 19 of each gate guide member is a lug 22, that occupies a position between the upper end of the flange 21 and the upper extremity of the curved flange 20, as seen most clearly in Fig. VI.

23 designates ears projecting inwardly from the flange 21 to receive bolts 24. (See Figs. II and VI.) These ears project through the gateways 14 and are secured to the uprights 11 of the door 11 to hold the lower ends of the gate-guide members firmly to the door.

By the use of a gate of the form described and guide members having flanges shaped and positioned as set forth I provide a construction by which the gates are securely maintained in either closed or open positions by reason of the frictional contact between the gate and guide members. This is due to the gates being pliable and resilient and the outer flanges of the guide-boxes being curved, as described, so that the gate will be flexed at all times to produce frictional contact between it and the flanges 20 and 21 and lugs 22 of said guide members, as seen in Fig. II.

25 I claim as my invention—

1. The combination with a grain-car door having a gateway, of guide members having curved flanges and secured to said door, and

a pliable resilient sheet-metal gate slidably positioned in said guide members for frictional contact against said curved flanges when the gate is shifted in said members, substantially as set forth.

2. The combination with a grain-car door having a gateway, guide members secured to said door and each having a straight flange and a curved flange, and a pliable resilient sheet-metal gate slidably positioned between said flanges for frictional contact therewith, substantially as set forth.

3. The combination with a grain-car door having a gateway, of guide members fixed to said door and each having a curved flange and a straight flange extending a portion of the length of said curved flange, and a lug positioned between the termination of said straight flange and the far end of said curved flange, and a pliable resilient gate slidably positioned between said flanges, and between said curved flange and said lug to bind between said parts when the gate is shifted in said member, substantially as set forth.

ANDREW G. STEINBRENNER.

In presence of—

NELLIE V. ALEXANDER,
M. P. SMITH.
